UNITED STATES PATENT OFFICE.

JOSEPH M. CESA, OF ANTIOCH, CALIFORNIA.

AIR-HEATING SYSTEM FOR FIREPLACES.

Application filed January 10, 1927. Serial No. 160,029.

This invention relates to improvements in means for heating and circulating air through the rooms of a house by means of the heat from the fire of an ordinary open fireplace; and particularly represents a modification or enlargement of the arrangement shown in my Patent No. 1,609,693 dated December 7th, 1926. In the previous device a blower was utilized to create an artificial air draft or current, which air was forced through the drum in the fireplace and issued thence in a heated condition from the registers or vents disposed at various points in the house. When the blower was not in operation there was no appreciable circulation of air through the drum, and therefore no heated air issued from the registers.

The principal object of the present invention therefore is to modify or enlarge the above arrangement of parts by providing means for enabling a natural circulation of air through the drum to be automatically maintained when desired, when the operation of the blower is discontinued, so that the heated air will continue to issue into one room or another to keep the air therein at a desirably high temperature. With this improved arrangement it is not necessary therefore to run the blower continuously in order to obtain the benefits from my air heating device and the cost of operation of the system over a given period of time may be considerably reduced.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a sectional elevation of an ordinary fireplace showing my improved air heating arrangement installed in connection therewith.

Fig. 2 is a fragmentary sectional elevation of the apparatus showing a modified arrangement of the hot air discharge pipe.

Referring now more particularly to the characters of reference on the drawings, the main features of the system, as before, comprise a vertically disposed rectangular drum 1 set against the back of the fireplace 2, the

drum projecting upwardly from the bottom of the fireplace to a point adjacent the chimney 3. The drum then turns outwardly to form a horizontal portion 4, from the outer end of which a downwardly projecting portion 5 depends, said latter portion being of course spaced from the front of the base of the chimney sufficient to enable the products of combustion from the fire in the fireplace to pass freely to and up the chimney. A longitudinal partition 6 in the drum extends from the bottom thereof to a point short of the bottom of the outer end portion 5. This partition divides the drum into two separated compartments 7 and 8, the former in the main rear portion of the drum being at the back of the fireplace. The bottom of the compartment 7 is connected to an intake pipe 9 which extends downwardly therefrom and is connected to the discharge of a blower 10 of suitable character located in the basement or elsewhere as may be desired. From the bottom of the compartment 8 a discharge pipe 11 leads under the floor 12 of the building, said pipe having one or more discharge registers or outlets 13 projecting into any desired room of the house to discharge the heated air into the same at a point adjacent the floor. The above parts are the same as shown and described in the previous patent, and it will be seen that when the blower is in operation the circulating air will pass upwardly through the pipe 9 into the drum, through the compartment 7 for the full length thereof, then into and through the compartment 8, and thence into the pipe 11 to discharge into the room through the register 13. This direction of the flow of air is shown by the solid arrows in Fig. 1. The air passing through the drum is heated by the heat from the fire in the fireplace so that when it issues from the register 13, said air is still in a heated condition.

With this arrangement there is no circulation of air to any appreciable extent when the operation of the blower is discontinued, as will be obvious. My additional feature which enables the desired circulation of air to be maintained when the blower is not in operation comprises an additional outlet passage leading from the top of the drum directly into a room at a level higher than that of the register 13. In the arrangement shown in Fig. 1, the fireplace is presumed as occupying an interior position in the build-

ing, so that there are rooms both in front of and behind the fireplace. In this case the additional drum outlet 14 preferably leads through the back of the fireplace into the 5 room beyond. In the arrangement shown in Fig. 2 the fireplace occupies a position in the exterior wall of the building, in which case the drum outlet 14^a projects forwardly of the drum into the same room as that in 10 which the fireplace is located. Both arrangements of outlet have a suitable shutter or damper device as at 15 arranged to be manually manipulated so that the outlet may be opened as much as desired or entirely 15 closed. The latter position of the shutter is had when the blower is in use so that said outlets 14 or 14^a do not then function.

If the blower is discontinued however the shutter is opened, and since the outlet 14 is 20 higher than the register 13 (toward which the colder air in the room naturally gravitates) a circulation of air from the register to the outlet 14 will be had. In other words 25 relatively cold air enters the pipe 11 from the register 13, moves along said pipe into the drum 1, along the compartment 8 (which is nearest the fire) for the full length thereof, and thence into the upper portion of the compartment 7 and out through the outlet 14 30 (or 14^a as the case may be). The direction of movement of this current of air is shown by the dotted arrows in Fig. 1 and, as will be evident, is the reverse of the direction had when the blower is operating. This re- 35 versed circulation of air by means of which hot air is discharged into a room from the upper drum outlet will continue as long as a fire is maintained in the fireplace or as long as the temperature in the room at the level 40 of the outlet 14 is greater than that at the level of the register.

From the foregoing description it will be readily seen that I have produced such a device as substantially fulfills the objects of 45 the invention as set forth herein.

While this specification sets forth in detail the present and preferred construction of the device, still in practice such deviations from such detail may be resorted to as do 50 not form a departure from the spirit of the invention, as defined by the appended claims.

Having thus described my invention what I claim as new and useful and desire to secure by Letters Patent is:

65 1. In combination, a drum to be mounted in a fireplace to be subjected to the heat of a fire therein, means dividing said drum into two vertical compartments, said compartments being arranged to communicate with each other at their upper ends, an intake 70 passage leading to the bottom of one compartment, an outlet passage leading from the bottom of the other compartment, said outlet

passage leading to a room, means for setting up a forceful circulation of air through the 65 drum compartments from the intake passage to the outlet passage, and another outlet from the drum; said outlets being arranged in height relative to each other so that when the operation of said circulating means is 70 discontinued a natural circulation of air may be set up from the first named outlet through one of the drum compartments to the last named outlet.

2. In combination, a drum to be mounted 75 in a fireplace to be subjected to the heat of a fire therein, means dividing said drum into two vertical compartments, said compartments being arranged to communicate with each other at their upper ends, an intake passage leading to the bottom of one compartment, an outlet passage leading from the bottom of the other compartment, said outlet passage leading to a room adjacent the floor 80 thereof, means for setting up a forceful circulation of air through the drum compartments from the intake passage to the outlet passage, another outlet from the top of the compartment of the drum to which the intake passage is connected, said last named 85 outlet leading to a room at a level higher than that of the first named outlet, and a manually operable shutter in said last named outlet.

3. In combination, a drum to be mounted 90 in a fireplace to be subjected to the heat of a fire therein, means dividing said drum into two vertical compartments, said compartments being arranged to communicate with each other at their upper ends, an intake 95 passage leading to the bottom of one compartment, an outlet passage leading from the bottom of the other compartment, said outlet passage leading to a room adjacent the floor thereof, means for setting up a force- 100 ful circulation of air through the drum compartments from the intake passage to the outlet passage, another outlet from the drum, leading to a room at a level higher than that of the first named outlet, and a shutter in 105 said last named outlet.

4. An air heating system comprising an air passage member to be mounted in a fireplace to be subjected to the heat of a fire 110 therein, an inlet to one end of said member, an outlet passage from the other end of the member leading to a room, means for setting up a circulation of air through the passage member from the inlet to the outlet, and another normally closed outlet from the passage member in spaced relation to the first named outlet and terminating in a room at a 115 higher level than said first named outlet.

In testimony whereof I affix my signature.

JOSEPH M. CESA.
